UNITED STATES PATENT OFFICE.

GERALD E. FORCE, OF NEW YORK, N. Y., ASSIGNOR TO HELMET CAP COMPANY, OF NEW YORK, N. Y.

COLLAPSIBLE-TUBE CLOSURE.

Application filed April 11, 1921. Serial No. 460,194.

To all whom it may concern:

Be it known that I, GERALD E. FORCE, a citizen of the United States, residing at New York, in the county of New York and 5 State of New York, have invented new and useful Improvements in Collapsible-Tube Closures, of which the following is a specification.

My invention relates to certain new and 10 useful improvements in receptacle closures and is capable of wide application in this field, although intended more particularly for use in connection with containers of the collapsible tube type in which tooth paste 15 and like substances are commonly sold.

Though I have shown the preferred use 20 of my invention in connection with collapsible tubes, the same is equally adaptable as a closure for automobile radiators, air plane radiators, and the like, preventing working loose and consequent loss of the cap by virtue of rough vehicular travel and constant vibration of the motor, respectively, as is prevalent with the general type of such 25 closures now in use.

The principal object of the invention is to provide a receptacle closure having cap-retaining means arranged to be concealed by the cap when the latter is in closed position, 30 to the end that the presentation of unsightly devices on the outside of the receptacle may be avoided.

Another object of the invention is to construct the receptacle and cap-retaining means that the latter serves not only to prevent complete separation of the cap from the receptacle, but also to facilitate re-engagement of the cap with the receptacle when returning the cap to closed position.

With these and other objects in view, 40 which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a view partly in elevation and 50 partly in section of a collapsible tube or container and closure constructed in accordance with my invention;

Fig. 2 is a similar view to Fig. 1 showing the cap or closure in open position; and

Fig. 3 is a perspective view of the con-

tainer showing the cap-retainer and disk guide member in relative position.

In the illustrated embodiment characterizing this invention, the collapsible container or tube 1 is of substantially conventional construction, being provided with a neck or collar 2 surrounding the discharge orifice and provided with an external screw thread 3 adapted to engage the internal thread 4 of the closure cap 5.

According to my invention there is provided a retaining member for hingedly connecting the cap to the container and, in the form herein disclosed, said retaining member comprises an inner cap-shaped circular 70 disk 6 threadedly engaged in the cap 5, as clearly shown in Fig. 2 of the drawing, and provided with an integral lug or guide member 7 projecting outwardly from the lower face thereof.

The lug or guide 7 is fitted into a slot 8 provided in the neck 2, and has its lower end pivotally secured in said slot, as indicated at 9.

With the above arrangement, and assuming that the parts are disposed as shown in Fig. 2, it is evident that when the disk 6 is swung downwardly to lie against the outer end of the neck or collar 2, the cap 5 can be readily threaded past the disk into engagement with said neck, thus closing and sealing the discharge orifice. It should be noted here, that the diameter of the disk is the same as the outside diameter of the neck and that the thread on the disk forms a continuation of the neck or collar thread. This is an important feature, as it enables the cap to pass smoothly from the disk onto the neck without the usual difficulty experienced in properly engaging the cap thread with 80 the neck thread.

When it is desired to dispense the contents of the container, the cap 5 is unscrewed from the neck 2 until its lower edge is substantially flush with the lower side of the disk 6, thus permitting said disk and cap to be swung to one side of the discharge orifice.

In order to hold the disk and cap against separation, the latter is provided interiorly with a central post 10 projecting from the top portion thereof and passing loosely through a central opening 11 in the disk, the free end of the post being enlarged to provide a stop 12 engageable with the lower side of the disk.

From the foregoing it will be seen that the cap-retaining means provided by my invention is entirely concealed from view when the cap is engaged with the neck 2, and this arrangement is desirable not only from the standpoint of preserving the usual outward appearance of the container, but also, because of the fact that the retainer is thereby shielded from damage or distortion by contact with other articles.

From the preceding it is apparent that I have designed a closure assembly for collapsible tubes or like containers, of great adaptability, eliminating the inherent deficiencies of those now in use, efficient in operation, simple in construction, and inexpensive to manufacture.

Although in the foregoing, certain elements may have been set forth as best adapted to perform the functions allotted to them, nevertheless, it is to be understood that various minor changes as to form, substance, etc., may be resorted to within the scope of the appended claims without departing from or sacrificing any of the principles of this invention.

Having thus described my invention, and without enumerating variations and equivalents, what I desire protected by Letters Patent is as set forth in the following claims:

1. A collapsible tube or similar receptacle, having a discharge orifice surrounded by an externally threaded collar, a guide pivoted to and operable to positions overlying and lateral of the collar, said guide being threaded, its threads constituting a continuation of those on the collar, and a cap carried by the guide and adapted to be disposed by the collar in a position for engagement with the threads of the collar.

2. A receptacle having an orifice surrounded by a neck, a closure retainer hinged to the receptacle and forming, in one position, a symmetrical extension of the neck and a cap carried by said retainer in reciprocal engagement therewith.

3. A receptacle having an aperture surrounded by a wall, a cap retainer hinged to the wall and a cap fitting over said retainer in threaded engagement therewith.

4. A receptacle having a discharge orifice surrounded by a threaded wall or collar, a cap-retainer hinged to the receptacle, and a cap threadedly engaged with the retainer and movable relative thereto into threaded engagement with said wall or collar.

5. A receptacle having a discharge orifice surrounded by a wall having a slot formed therein, a cap retainer having a projection pivotally secured in said slot, and a cap carried by said retainer and movable relatively thereto into and out of engagement with said wall.

6. A receptacle surrounded by a threaded wall having a slot formed therein, a cap-retainer normally disposed to form a symmetrical continuation of the wall, a projection from the cap-retainer pivotally secured in said slot, and a cap threadedly engaged with said retainer and movable relative to the retainer into and out of threaded engagement with said wall.

7. In combination, a receptacle, a closure therefor, and retaining means threadedly engaged with the closure and arranged to be entirely concealed thereby when in receptacle closing position.

GERALD E. FORCE.
